SCAFFOLDING DEVICE

Frank A. Yench, Two Rivers, Wis.

Application April 25, 1949, Serial No. 89,489

1 Claim. (CL 304—3)

1

This invention relates to an improved scaffold structure.

An object of this invention is to provide an improved scaffold structure which combines a ladder as one portion thereof with a platform support. It is contemplated that this device be used with an extensible ladder so that the platform may be vertically adjusted.

Another object of this invention is to provide a scaffold structure which will be rigid when set up, and at the same time can be taken down and set up very quickly.

A further object of this invention is to provide a scaffold unit for use with a pair of ladders of the fixed or extensible type, which will permit the separate use of the ladders, and the quick connection between the scaffold structure and the ladders so as to form a rigid scaffold.

With the above and other objects in view, my invention consists in the arrangement, combination and details of construction disclosed in the drawings and specification, and then more particularly pointed out in the appended claim.

In the drawings,

Figure 1 is a detail side elevation of a scaffold structure constructed according to an embodiment of this invention,

Figure 2 is a sectional view taken on the line 2—2 of Figure 1,

Figure 3 is a sectional view taken on the line 3—3 of Figure 2,

Figure 4 is a fragmentary sectional view taken on the line 4—4 of Figure 2,

Figure 5 is a fragmentary sectional view taken on the line 5—5 of Figure 2,

Figure 6 is a fragmentary sectional view taken on the line 6—6 of Figure 2,

Figure 7 is a fragmentary sectional view taken on the line 7—7 of Figure 1,

Figure 8 is a fragmentary sectional view taken on the line 8—8 of Figure 2,

Figure 9 is a fragmentary sectional view of the lower end of one of the uprights,

Figure 10 is a view similar to Figure 9, showing a modified form of anti-slipping means for the uprights.

Referring to the drawings, the numerals 15 and 16 designate generally a pair of ladders which may be either long single length ladders or extension ladders of conventional construction. In order to combine the ladders 15 and 16 to form a scaffold structure with the ladders leaning against the side of a building, I have provided a pair of upright extensible supports 17.

The upright 17 includes an upper elongated

2

tubular member 20 telescoping over the lower tubular member 18, and a pair of these uprights are braced in vertical position by means of a pair of crossed brackets 21 and 22. The tubular members 18 and 20 are formed with spaced openings 23 and 24 respectively, which are adapted to be disposed in registry and the tubular members 18 and 20 are secured in longitudinally adjusted position by means of bolts 25 extending through selected registering openings 23 and 24. These bolts 25 also secure the ends of the braces 21 and 22 to the uprights.

The uprights are held in a vertical position parallel with the wall 26 against which the ladders 15 and 16 lean by means of a pair of Y-shaped combined braces and platform supporting members 27. The members 27 include a pair of divergent arms 28 and an elongated shank or stem 29. The shank or stem 29 is extended through a loop or U-shaped member 30 which is fixed to an upper tubular member 20 and the shank or stem 29 is locked in the loop 30 by means of a set screw 31.

The divergent arms 28 are pivotally secured to a pair of U-shaped members 32 which are fixed to the lower ends of a pair of downwardly extending rods 33 which are carried by caps 34. The caps 34 engage over the upper ends of the rails of the ladders 15 and 16 and the rods 33 extend parallel with and closely adjacent the forward edges of the ladder rails.

The arms 28 are pivotally secured to the coupling members 32 by means of a bolt 35. The lower end of each upright is anchored relative to the lower end of a ladder by means of a pair of anchoring bars 36 which are formed at their outer ends with a loop 37 through which the rail of a ladder is adapted to engage. The inner ends of the anchoring bars 36 are bent right angularly to form ears 38, and a bolt 39 is extended through the ears 38 and through the lower portion of the lower tubular member 18.

The combined Y-braces and platform supporting members 27 are adapted to have boards 40 mounted thereon, and a safety bar or cable 41 is secured between the upper ends of the uprights 17, being secured to caps 42 having ears 43. The lower end of lower member 18 may have a rubber cap or foot 44 mounted thereon as shown in Figure 8, or may have a point 45 secured thereto as shown in Figure 10.

In the setting up of the scaffold hereinbefore described, the ladders 15 and 16 are disposed in a leaning position against the wall 26. The platform supporting members and braces 27 are sup-

ported from the upper ends of the ladders by the caps 34, and the tubular members 20 are then raised to the desired height so that the platform supporting members 27 will be in a horizontal position for engagement through the keepers or loops 30. The upper tubular members 20 are secured in extended position by the bolts 25 which also provide the securing means for the crossed braces 21 and 22. The scaffold structure hereinbefore described will provide a relatively simple means whereby a carpenter, painter or the like may work on the outer side of a building with a minimum of equipment. As hereinbefore described, the ladders 15 and 16 may be either single length or extensible ladders and where extensible ladders are used the platform may be raised or lowered to the desired degree by extending or retracting the ladder section.

I do not mean to confine myself to the exact details of construction herein disclosed, but claim 20 all variations falling within the purview of the appended claim.

What I claim is:

A scaffold comprising a pair of uprights, each upright formed of a pair of telescopically arranged 25 members, means securing said members in lengthwise adjusted position, crossed braces fixed between said uprights, a pair of ladders disposed one adjacent each upright and diverging upwardly

from the lower ends of said uprights, a pair of horizontally disposed Y-shaped members, a pair of bars at the upper end of each ladder, caps carried by said bars engaging over the upper ends of the ladder rails, a pair of ears fixed to the lower ends of each bar, means pivotally securing the divergent arms of said Y-shaped members between said ears, a loop fixed to each upright, and means adjustably securing the shank of said Y-shaped member in said loop, a guard rail, and means securing said guard rail to the upper ends of said uprights.

FRANK A. YENCH.
